UNITED STATES PATENT OFFICE.

THOMAS JAMES SCOTT, OF WINCHESTER, TENNESSEE.

COMBINED BOOKCASE AND VAULT THEREFOR.

1,110,721.

Specification of Letters Patent. Patented Sept. 15, 1914.

Application filed September 20, 1913. Serial No. 790,860.

To all whom it may concern:

Be it known that I, THOMAS JAMES SCOTT, residing at Winchester, county of Franklin, and State of Tennessee, have invented a new and Improved Combined Bookcase and Vault Therefor, of which the following is a specification.

My invention has for its object to provide a simple and effective means for storing books, files, and other valuable papers which, under normal conditions, serves as a combined book and file case, and which is readily shifted into a vault-like compartment for safe-keeping of the books and files and the casing or shelves upon which they are held.

Among other objects, my invention has for its purpose to provide a means of the general character stated, in which the book and file holding casing forms a part of the closure for the vault, and in which the operation of raising and lowering the book and file holding casing may be effected manually or automatically and the transferring of the casing containing the said books, etc. accomplished without the necessity of disarranging or removing any of the books etc. from the casing shelving.

Another object of my invention is to provide a simple and convenient arrangement of a shiftable book and file holding casing, especially designed that the books may be supported for convenient use during the day surrounded by a frame work constructed to serve as a desk or table.

With further objects in view, that will hereinafter appear, my invention consists in certain details of construction and novel arrangement of parts, all of which will be hereinafter fully explained, specifically pointed out in the appended claims, and illustrated in the accompanying drawings, in which:

Figure 1 is a perspective view that illustrates the external arrangement and design of my invention. Fig. 2 is a front sectional elevation thereof, the book casing being shown down in the vault at the safety position, parts being in section to the more clearly illustrate their structural arrangement. Fig. 3 is an end elevation thereof, parts of the casing being broken away. Fig. 4 is a horizontal section of my improvements taken on the line 4—4 on Fig. 2. Fig. 5 is a perspective view of the book case or shelving, parts being broken away. Fig. 6

is a perspective view of the bottom end of the said book case and more particularly illustrates the arrangement of the truss rods hereafter referred to: Fig. 7 is a detail perspective view of the upper end of the casing receiving vault, portions of the uprights or guide frame members being also shown. Fig. 8 is a cross section on the line 8—8 on Fig. 7.

While my invention is adapted for use in any kind of a building, and on any of the floors thereof, it is more especially designed for court house uses where there are no fire-proof vaults.

In the drawing, I have shown my invention arranged as a wall book-casing or shelving combined with front and side desk portions, but I desire it understood my said invention may be readily arranged in the center of the room and a pair of abutting shelf casings or frames, joined to move together into and out of the vault or pit into which they are lowered when the books and files are stored for safe-keeping.

My combined book and file case and vault can be made of any suitable size. In the drawings, in which I have illustrated a preferred proportionate arrangement of the parts, 1 designates the floor of the room and 3 a fire-proof vault or pit into which the shelf or framing is lowered when it is shifted to the place of safety.

2 designates the book or file casing, formed of metal and which comprises the end members 20, a back 21 and the top and bottom members 22—23.

The top of the book casing comprises a plate 24 that fits over the shelving and the end portions of the casing, angle irons 25 secured around the upper edge of the casing that extend above the said edge to form a space 26 between the plate 24 and a supplemental plate 27 that is secured to the said angle irons in any suitable manner. The bottom of the book and file casing has angle irons 28, attached and these form pendent flanges 29 that strengthen the said bottom and also provide means for conveniently securing the ends of a pair of truss rods 30 that take over a bridge 39 formed by the pair of angle irons 28 that extend across wise over the said casing bottom, see Fig. 6. The vault or pit 3 into which the book casing is lowered and which is fire-proof, has its upper end flush with the top of the desk portions 4—5 and it ex-

tends down through the floor a required distance for receiving the casing when it is lowered, and so that the top of the latter will be flush with the said desk portions 5 4—5 as is clearly shown in Fig. 2. At the upper or mouth end, the vault is formed with a surrounding angled off-seat 6 and the latter is sheathed by a metal lining 7 to provide for a substantially air tight fit 10 of the casing top over the vault, the said top, forming, as it were, the closure for the vault. The portions 8 of the upper angle plates form the closure rim that engages the off-sets or seats 6 in the upper edge of the 15 vault and the top plate 27 has its ends and sides extended beyond the said angle iron portions 8, and notched as at 9, the reason for which will presently appear. Vertical guide grooves 10 are formed on each end 20 member of the casing and they are made by attaching a pair of angle plates 11—11 to the said casing ends. The guides 10 serve to hold the casing steady as it is raised or lowered in the vault by engaging the 25 guide cleats 12 on the end walls of the vault as shown.

By reason of the peculiar construction of the parts, so far described, it is obvious that when the casing is lowered into the 30 vault the top of the casing forms a part of the desk top and when elevated, the casing with the shelves, rises from and forms, as it were, a part of the complete desk structure. To keep the vault dry, the vault walls 35 are formed with a dead air space 13 that surrounds the vault well or pit and which however does not communicate with the vault pit or well.

In the practical arrangement of my invention the means for supporting the casing and for raising and lowering it are housed in, the housing being of ornamental shape to give the desk and housing suitable ornamental finish and design. As shown in 40 Fig. 1, the housing is of paneled form and has a front opening 16 that is snugly filled by the book casing when the same is raised. The housing includes the vertical end portions 18 that close in the supports for the 45 book casing and the elevating devices.

31—31 designates vertical posts, one at each end of the vault, see Fig. 7, each of which has an inside cleat or guide 32 for engaging the notches 9 in the casing top 50 plate 27.

33 designates a hanger shaft journaled on the upper end of the posts 31 and which carries the winding pulleys 34 to which are secured the hanger cables 35 the lower ends 55 of which attach to the top of the casing as shown.

36 designates a sprocket pulley over which passes the sprocket chain 37 that takes over a bottom sprocket wheel 38 journaled in a stub shaft 39 projected from the adjacent 65 supporting standard, and which carries a gear worm 40 that meshes with a worm driver gear 41 on a crank shaft 42 the handle end of which is located outside of the housing, see Fig. 1 and carries a ratchet 43, 70 for coacting with the usual locking pawl.

It will be noticed from Figs. 3 and 7 that the hanger shaft is mounted at the rear of the supporting posts and that the flanges of the winding pulleys have their rear edge 75 in vertical alinement with guide cleats 44 formed upon the inner face of a pair of supplemental posts 45, (see Fig. 7) to provide for a free and easy lift of the counterpoise or weights 46 whose ends are notched as at 80 47 for engaging the said cleats 44.

To further insure safety of the book casing and its contents, when the same is lowered, bolts 48 are secured upon the opposite ends of the top plates 27 and they are adapted to interlock with the base of the standards 31—31 when the said casing is down, as shown in Fig. 2.

49 designates fusible links in the cables or ropes on which the book casing is suspended 90 and they are provided to insure a positive drop of the casing into the vault in case of fire.

50 designates a door or flap member for closing the opening between the top of the 95 desk 4 and the book casing when the latter is raised as in Fig. 1.

What I claim is:

A combined book case and vault therefor, comprising a desk platform having an opening, a vault whose upper end terminates at the opening in the desk platform, a book case vertically movable within the vault, guides on the inner walls of the vault that hold the ends of the book-case spaced from the wall ends, guides on the book-case that co-act with the vault guides, supports that extend up from the platform at each end of the vault and which include two guides, the said book-case including a top whose edges form members that close over the space between the book-case and the vault sides when the book-case is lowered into the vault, the said top edges also having guide grooves for engaging the guides on the vertical supports when the book-case is elevated, and means operative above the platform for raising and lowering the book-case.

THOMAS JAMES SCOTT.
